UNITED STATES PATENT OFFICE.

DETLEF VON BOTTEKE, OF BALTIMORE, MARYLAND.

FIRE KINDLER.

Application filed June 8, 1927. Serial No. 197,247.

This invention relates to stoves, furnaces and like heaters and more particularly to types using coal as a fuel.

In the past, when it was desired to build a fire in such stoves it was necessary to first burn paper, then wood and finally coal in order to bring the temperature of the fire up to the ignition point of the coal.

Obviously, such a method is slow and tedious, requiring great care to see that the fire does not go out or become smothered through lack of oxygen.

It is therefore the main object of this invention to provide simple and quick means for raising the temperature of the coal to its ignition point, thus eliminating the need of burning fuel having lower ignition points than the coal.

A further aim is in the provision of a guard adapted to protect the coal heating means against clogging, thus assuring positive operation at all times.

A still further characteristic is to provide coal heating means which, when the fuel has reached its combustion point, may be shut off.

These and other objects, which will become apparent as the description progresses, are attained by the novel construction, combination and arrangement of elements, hereinafter delineated and depicted in the accompanying illustration, constituting an important component of this disclosure, and in which:

35 Figure 1 is a front elevational view of a furnace equipped with an embodiment of this invention, part of the casing being broken away to show the inner construction.

Figure 2 is a transverse sectional view 40 taken on line 2—2 of Figure 1.

Figure 3 is a fragmentary side elevational view of the coal heating means, drawn to an enlarged scale.

Figure 4 is a top plan view of the same 45 taken in a plane at right angles to Figure 3, the anti-clog guard being removed.

Figure 5 is a partial transverse sectional view taken on line 5—5 of Figure 3 drawn to a further enlarged scale.

50 Figure 6 is a partial transverse sectional, partial top plan view taken on line 6—6 of Figure 7.

Figure 7 is a front elevational view showing the application of this invention to a 55 type of boiler, the embodiment having been indicated in broken lines.

In the drawing, the numeral 10 generally designates a furnace of the coal burning type having various compartments, shelves, etc., all of the usual construction.

One of the side walls of the furnace is lined with a fairly thick sheet 11 of fire brick or other heat resisting material and rising from the floor of the furnace, spaced from the wall 11, approximately half the height thereof, is a thinner metal partition 12.

Intermediate the partition 12 and wall 11, near the top of the former, is a grate 13 supported by brackets 14 fixed to the wall 11 and partition and secured to the same, near the bottoms thereof, is a second pair of oppositely disposed brackets 15 supporting a metal plate 16 on which there is a pan 17 to catch whatever material may fall between the interstices of the grate 13.

Passing through the sheet 11 and the adjacent side wall of the furnace, just below the grate 13, is a pipe 18 connected to a supply of gas, the pipe being bent at a right angle to form a burner 19 having an integral T-portion 20, disposed in the same horizontal plane, the burners being provided with double rows 21 of apertures from which gas may flow to be burned and the T-portion being supported on brackets 22.

Secured by bolts 23 on the ends of the burner 19, are clamps 24 to which is fixed an elongated, transversely arcuate guard 25, spacedly covering the openings 21 against cinders, etc. from the grate 13.

In Figures 6 and 7, the numeral 30 designates an outer, cylindrical casing in which is placed an inner, eccentric casing 31, provided with a grate 32 below which is disposed a burner 33 of the type above described, supplied with gas through a pipe 34.

Thus, when it is desired to build a fire, a quantity of coal is placed on the grate and the gas burner is lit so that the flames therefrom reach the coal and heat the same until a temperature is attained surpassing the ignition point of the coal.

As soon as the fuel has taken fire, the gas may be shut off and the fuel will continue to burn.

Obviously this method eliminates the necessity of first burning paper, then wood and finally coal, which as previously stated, is slow and inconvenient in the present era of comfort and speed.

Having thus described my invention, what

I claim as new and desire to secure by Letters Patent, is:—

In a coal burning fire box having a grate and an ash pit, an integral cruciform pipe having a plurality of perforations in its upper wall, said pipe being connected to a gas supply and disposed in said ash pit adjacent below said grate, and a unitary con-

vex cover removably engaged in spaced relation to said pipe to prevent droppings from the grate entering the mentioned pipe perforations.

In witness whereof I have affixed my signature.

DETLEF v. BOTTKE.
